US0D1013583S

(12) **United States Design Patent** (10) Patent No.: **US D1,013,583 S**
(45) Date of Patent: ** Feb. 6, 2024

(54) **MUD GUARD**

(71) Applicant: **BEIJING XIAOMI MOBILE SOFTWARE CO., LTD.**, Beijing (CN)

(72) Inventors: **Zhenhua Liu**, Beijing (CN); **Lei Zhang**, Beijing (CN)

(73) Assignee: **Beijing Xiaomi Mobile Software Co., Ltd.**, Beijing (CN)

(**) Term: **15 Years**

(21) Appl. No.: **35/514,047**

(22) Filed: **Sep. 17, 2021**

(80) **Hague Agreement Data**

Int. Filing Date: **Sep. 17, 2021**

Int. Reg. No.: **DM/219927**

Int. Reg. Date: **Sep. 17, 2021**

Int. Reg. Pub. Date: **Apr. 15, 2022**

(30) **Foreign Application Priority Data**

Mar. 17, 2021 (CN) 202130144016.0

(51) **LOC (14) Cl.** **12-11**

(52) **U.S. Cl.**

USPC **D12/114**

(58) **Field of Classification Search**

USPC D12/114, 110, 126, 184, 186

CPC B62J 9/23; B62J 15/00

See application file for complete search history.

(57) **CLAIM**

The ornamental design for a mud guard, as shown and described.

DESCRIPTION

1.1 is a front view of a mud guard;

1.2 is a back view of the mud guard;

1.3 is a left view of the mud guard;

1.4 is a top view of the mud guard; and

1.5 is a perspective view of the mud guard.

The broken lines in FIG. 1.5 illustrate a portion of the article which forms no part of the claimed design.

1 Claim, 3 Drawing Sheets
